UNITED STATES PATENT OFFICE

ROBERT C. PAULY, OF CINCINNATI, OHIO, ASSIGNOR TO THE AMERICAN LAUNDRY MACHINERY COMPANY, OF NORWOOD STATION, CINCINNATI, OHIO, A CORPORATION OF OHIO

PRESS CLAMP

Application filed April 30, 1928. Serial No. 273,886.

This invention relates to pressing machines and particularly to work holding and stretching devices therefor.

The object of the invention in this case is to provide means for holding the work on the bed of a pressing machine with the work holding means arranged to clamp the work in different positions and to provide stretching devices which are beyond the bed and which may be brought into play to stretch different parts of an article over the face of the bed. For example, the present invention is designed for the general utility in laundry work where various articles must be held and where some parts must be stretched. The invention is particularly adaptable to machines for certain types of laundry work where shirts are ironed and where the press is not provided with a neckband former or clamp.

The various features of the invention will be brought out in the following description, drawings and claims.

Referring to the drawings, Fig. 1 is a perspective view of a press provided with the invention; Fig. 2 is a side elevation of a portion of the board or bed showing one of the clamping devices; Fig. 3 is a rear elevation of the same part; Fig. 4 is a detail view showing the swivel connection of the clamping band to the frame indicating the adjustment of the tension on the band as well as the tensioning means for holding the band in its different positions; Fig. 5 is a similar view showing the connection of the band to the frame at the front of the machine; and Fig. 6 is a view partly in section and partly in elevation showing one of its stretching devices.

In the embodiment shown in the drawings, 1 represents the press main frame supporting a work table 2 above which is the board or bed 3 having a reduced end 4 for convenience of use in various places such as, for instance, supporting portions of the front of a shirt adjacent the neckband as shown in Fig. 1. Cooperating with this bed is a heated ironing chest 5 having a reduced forward portion 6 cooperating with the portion 4. The bed and head are matched in the sense that they are coextensive in area and cooperating in contour of their ironing faces. The

bed is padded as usual and is adapted to receive the work.

Extending from the underside of the bed are a pair of transversely arranged front and rear brackets 7 and 8 adapted to receive the clamping frame having its cross member 9 supported in the brackets and a front upstanding arm 10 and a rear upstanding arm 11. These arms are beyond the front and rear edges of the board so as to swing clear thereof.

The front arm 10 is provided with a suitable manipulating handle 12 and beyond this a suitable eye 13 receiving the shank 14 having a swivel eye 15 connected to a clevis block 16 secured to the clamping band 17. The shank 14 is headed over at 18 so as to hold the parts together and yet permit a free swivel of the band 17 and its connected part at this point.

The rear arm 11 is threaded at 19 and receives at its end an eye block 20 adapted to receive a threaded shank 21 of the swivel eye 22 which in turn is pivoted to a clevis block 23 secured to the other end of the band 17. Engaging the threaded shank 21 is a thumb and check nut structure indicated at 24 and adapted to engage a spring 25 inserted between this check nut structure and the eye block 20 to create a cross tension upon the band and permit of adjustment of this tension. The threaded portion 19 of the rear arm 11 is provided with a spring clip 26 held between check nuts 27 and adapted to be connected to the upper end of a spring 28 extending down and secured to the bracket 8 at the screw eye 30. This spring, as shown in Fig. 3, passes to the left of the axis of the cross member 9 of the clamping frame when the clamp is in the left position. As it is moved to the right, this spring crosses the axis of this same cross member 9 and passes beyond the same to the right so that it will hold the clamping band tightly upon the work on the bed in either of the two positions.

Secured to the work board or any other suitable support beyond the end of the ironing board, preferably the reduced end 4, are stretching devices and they comprise preferably a spring wire support or core 31 hav-

ing an eye secured to the work board by a suitable bolt structure 32 and extending upward through a coil spring 33 which is wound in what might be termed solid formation so that it possesses some more or less rigid supporting characteristic. This spring is longer than the core wire 31 and at its upper end is screwed or otherwise secured in a socket 34 carrying a cross pin or screw 35 adapted to receive the eye 36 of a spring clamp comprising opposed thumb and finger portions 37 and crossing jaws 38 adapted to be snapped onto the edge of a garment beyond the end of the board to create a pull or stretch. Two of these are shown, one near the forward edge of the board and one near the rear edge so that they may be manipulated in the most handy fashion to stretch the garment as desired. By reason of their arrangement and mounting, they stand up in ready position for access to the operator and are extremely effective in producing the stretching operation.

In use the operator may use the clamp in any desired manner throwing it from one side to the other and thereby clamping articles in the best way possible according to the treatment they are to receive. He may also use the stretching devices in any way he sees fit. In one use, as shown in the drawings and in this disclosure, a shirt is being treated and its tail portion is being held by the clamp, swinging to the right, while the neckband is being pulled over the end of the board by one of the stretching devices. With little practice these devices may be utilized with great effect in holding articles on boards of ironing machines.

What I claim is:

- 40 1. In a pressing machine, a bed, a transverse work clamp mounted for swinging movement to substantially two different clamping locations upon the bed, supporting means therefor positioned to support said clamp in its different locations, and a tension device effective upon said clamp in its different locations.
- 45 2. A pressing machine as set forth in claim 1, characterized in that the supporting means comprises a transverse swinging frame within the ends of the bed and adapted to support said clamp in its different locations upon the bed.
- 50 3. A pressing machine as set forth in claim 1, characterized in that the supporting means comprises a U-shaped frame pivoted below and transversely of the bed and having upwardly projecting side arms, and characterized further in that the tension device is connected to said frame and adapted to create tension upon the clamp in each of its locations upon the bed.
- 55 4. In a pressing machine, a bed, a U-shaped clamping frame pivoted beneath the bed and having its side arms extending up along the

sides thereof, a clamping strap swivelled in the ends of the side arms and adapted to engage the bed transversely, and means for adjusting the tension on said strap.

5. In a pressing machine, a bed, a U-shaped clamping frame pivoted beneath the bed and having side arms extending beyond and having movement along the sides of said bed, a clamping strap swivelled in the upper ends of the side arms and adapted to engage the bed transversely, and means for adjusting the tension on said strap, said means comprising a threaded shank carried by the end of the strap, an eye on a frame side arm for receiving said shank, a wing nut on said shank, and a spring surrounding said threaded shank between said wing nut and the side arm.

In testimony whereof I hereby affix my signature.

ROBERT C. PAULY.
